UNITED STATES PATENT OFFICE

2,692,415

SAFETY PIN

Thomas P. Forde, Elmhurst, N. Y.

Application July 2, 1951, Serial No. 234,794

3 Claims. (Cl. 24—156)

1

This invention relates to safety pins.

It has been found that the present commercial safety pin is often swallowed by children and the object of this invention is to provide a safety pin which resists swallowing of the same, and shall be practical for all general use. Also, another object of the invention is to provide a safety pin which can only be opened in a particular manner, whereby the child is unable to open it.

The invention comprises a pin member having hinged thereto, a spring actuated member, preferably bent into angular shape providing an elbow, the pin member supporting a sheath for enclosing the sharpened end of the pin. This sheath, is of particular form, to guide the pin end in a labyrinthical manner to a safety position, which pin does not unclasp save by a guided hand movement by one familiar with its manner of operation.

The invention will be further described, embodiments thereof shown in the drawings, and the invention will be finally pointed out in the claims.

In the accompanying drawings,

Fig. 1 is a perspective view of the improved safety pin;

Fig. 2 is a top view of the same;

Fig. 3 is a side view of the closed pin;

Fig. 4 is a detail view taken on line 4—4 of Fig. 2;

Fig. 5 is a side view with the pin open;

Fig. 6 is a vertical section on line 6—6 of Fig. 4;

Figs. 7, 8 and 9 are views showing a modification with Fig. 7, a top view of the pin tip holder;

Fig. 8 is a side view of the pin tip holder, and

Fig. 9 is a side view of the spring end.

Similar characters of reference indicate corresponding parts throughout the various views.

Referring to the drawings, the pin shank 10 has one end 11 pointed or sharpened in the manner usual to enable entrance of the pin into the materials to be held. The other end of the shank 10 has a handle portion 12, and inwardly of the same is a shoulder 13 with a bore 14.

A sheath 15 is supported at one end 16 of a bow shaped member 17 which has a trunnion holding part 18, and which extends beyond the same to form the handle 19, a pintle 20 passes through a bore 21 of the part 18 and through the bore 14 of the shoulder 13 of the pin shank. The bores 21 and 14 register with each other, with the pintle 20 passing through the bores to form a hinge. A spring 22 presses against both handles at their inner sides, one end of the spring being fixed as at 23 by welding, or the like. The spring 22 is com-

pressible and when pressure is released it expands to its normal position giving a closing bias to the pin.

The sheath of the end 16 is of specific shape. It is welded or otherwise secured to the end 16 as shown by 24. It is constructed of a semi-circular cup member 25, which has at its upper ends 26 and 27 bent over portions. The part 28 at 26 is bent down, and the part 29 at 27 is longer than the part 28 and is also bent down but it extends beyond the medium of the semi-circular portion 25. Any movement of the pin 10 tends to move it either to the right or to the left, and in either event the pin is captivated by the corners formed 15 within the bends 26 and 27. Only when the pin is guided along the lower surface of the part 29 and then over the end of the shelf 29, and upwardly in reverse to the arrow 30, is it possible for the pin to escape. This labyrinthical sheath is a small length as shown in Fig. 2.

The ends or lips 28 and 29 converge towards each other downwardly, and the tips thereof are about on a radial plane passing through the median part of the semi-circular cup, about at its lowermost part. (Fig. 6.) Any accidental downward pressure on the pin 10 when it is in one of the pockets, causes the pin to move along the inner semi-circular contour of the cup or semi-circular portion 25, and thus the pin 10 is more likely to move into one or the other pocket than pass out of the space 30.

The modified form shown in Figs. 7 to 9 is substantially the same, save that the handle 19 has a bent over portion 19a holding the spring 22. Also the bow shaped member 15 has its end bent to enter a sleeve 35 formed in the sheath so as to be secured thereto. Also the bow shaped member 15 has at its extreme end tongues 35—35.

A hole 36 is provided at the bottom into which the bent over member 17 passes and is clinched together tight by the two tongues 35—35.

The parts 28 and 29 are of different lengths as shown in Figs. 2, 3, 4, 5, 7 and 8.

From the foregoing it is seen that the invention consists of a combination of a sharpened pin, a pin end sheath, a member supporting said sheath and hinged to said pin, said sheath having a circular portion having bent over ends, one end portion being of greater length than the other, 45 with the tips of said ends or lips being generally aligned and spaced from each other forming an outlet for the pin, the inner sides of the ends or lips forming pin holding means preventing the pin from moving into said outlet, save by a guided 50 movement.

I wish it to be understood that I do not desire to be limited to the exact details of construction shown and described, for obvious modifications will occur to a person skilled in the art.

I claim:

1. In a safety pin, the combination of a pin having a sharpened point, a sheath for the pin end of the pin, a member supporting said sheath having a semi-circular cup portion, a hinge connecting said pin and said member, the median outside of said sheath being secured to said member, and having bent-over lips forming inclined walls converging downwardly towards each other, one lip being of greater length than the other lip, with the tips of said lips being aligned in a radial plane passing through said median of said semi-circular portion, and spaced from each other at least the thickness of said pin, forming an outlet for the pin, the inner inclined sides of said lips each forming a pin holding pocket with said semi-circular portion, preventing the pin from moving into said outlet, save by a guided movement.

2. The structure of claim 1, in which the pivot of the sheath holding member is located inwardly of the end of the pin distant from its sharpened point, and said sheath holding member has an angularly disposed end forming an angle with

the pin beyond said hinge, and a spring is interposed between both of said ends, whereby pressure on said end of the pin and on the angular portion of sheath supporting member serves to hold separate the point of the pin from sheath, when said point has been disengaged from said sheath.

3. The structure of claim 1, in which the sheath holding member has an angularly shaped bow shaped portion with its angle distant from said pin.
